(57) **CLAIM**

The ornamental design for a drive unit for a blender, as shown and described.

DESCRIPTION

FIG. 1 is a bottom, front, right side perspective view of a drive unit for a blender showing our new design;

FIG. 2 is a front elevational view of the embodiment of FIG. 1;

FIG. 3 is a rear elevational view of the embodiment of FIG. 1; FIG. 4 is a left side elevational view of the embodiment of FIG. 1;

FIG. 5 is a right side elevational view of the embodiment of FIG. 1;

FIG. 6 is a top plan view of the embodiment of FIG. 1; and, FIG. 7 is a bottom plan view of the embodiment of FIG. 1.

The broken lines of FIGS. 1-7 represent unclaimed portions of the drive unit for a blender and form no part of the claimed design.

1 Claim, 7 Drawing Sheets
